UNITED STATES PATENT OFFICE.

PERRY JOHNSON, OF CINCINNATI, OHIO, ASSIGNOR OF ONE-HALF TO
AUGUSTUS G. BOFINGER AND LEWIS G. HOPKINS, BOTH OF SAME
PLACE.

STEAM-BOILER FURNACE.

SPECIFICATION forming part of Letters Patent No. 293,654, dated February 19, 1884.

Application filed December 31, 1883. (No model.)

To all whom it may concern:

Be it known that I, PERRY JOHNSON, of Cincinnati, Hamilton county, Ohio, have invented a new and useful Improvement in 5 Steam-Boiler Furnaces, of which the following is a specification.

My invention relates to those furnaces in which a shutter is located in advance of the combustion-chamber, and has for its object a 10 construction of steam-boiler furnace adapted to secure complete combustion of the fuel, and to permit the use of divers kinds of fuel in one and the same furnace without the production of unconverted smoke. With this object 15 in view I dispense with the customary bridge-wall, and I provide back of the fire-place a pit or reverbratory chamber, within which the unconsumed carbon and gases circulate and are consumed, and within which also the non- 20 combustible solid matters are precipitated, the non-combustible gases escaping into the flues from the rear upper part of said chamber through a narrow throat capable of being opened to a greater or less extent, or completely closed by means of a vertically-sliding gate or shutter under control of the person in 25 charge.

In the accompanying drawings, Figure 1 is a longitudinal section, and Fig. 2 a transverse 30 section of a single boiler-furnace provided with my improvement. Fig. 3 is a transverse section, showing its application to a double-boiler furnace. Fig. 4 is a perspective view, showing my gate and its operating-lever as 35 used with a two-boiler furnace.

A may represent a common horizontal boiler with a return-flue; B, its fire-chamber; C, fire-grate, whose rear edge is supported on a pier, D, that rises very little or not at all 40 above the grate-floor, and which constitutes the rear wall of the ash-pit.

In rear of pier D, and extending under the boiler for its whole remaining length, is a reverberatory chamber, E, whose floor shelves 45 away from said pier top to the foot of the pier F, that supports the rear end of the boiler. The portion of the top of the pier F not

employed in supporting the boiler is concaved out, so as to afford a crescent-shaped throat, G. A pit, f, in the concave top of the 50 pier F receives and permits vertical play of a pier F receives and permits vertical play of a gate or shutter, H, whose top h is concaved, to fit the lower part of the boiler, and which is guided to a vertical path by the pit sides or other means. A lever, J, whose short arm 55 extends underneath the gate H has its longer arm extending to a point outside the furnace convenient to the operator, a rack, K, being provided to hold the lever to any place of adjustment. Through the thus restricted throat 60 G the gaseous non-combustibles escape into flue L.

I claim as new and of my invention—

1. In a steam-boiler furnace, the combination, with a boiler, of a grate whose rear end 65 is level with its supporting-pier, a gradually-shelving combustion-chamber, which extends underneath the boiler its entire length in rear of said pier, a pier at the rear end to close the said combustion-chamber at bottom, formed 70 with a vertical opening, and having its top concaved out to conform to the shape of the lower part of the boiler to form a narrow throat, and a gate or shutter to slide in said opening to regulate the width of or to close 75 the throat, as set forth.

2. In a steam-boiler furnace, the combination, with boilers, of a grate whose rear end is level with its supporting-pier, a gradually-shelving combustion-chamber, which extends 80 underneath the boilers their entire length in rear of said pier, a pier at the rear end to close the said combustion-chamber at bottom, formed with a vertical opening, and having its top concaved out to conform to the shape 85 of the lower part of the boiler to form a narrow throat, and a gate or shutter to slide in said opening to regulate the width of or to close the throat, as set forth.

3. In a steam-boiler furnace, the combination of a grate-support about level with the grate, a combustion-chamber having a floor shelving downwardly from the grate-support, a pier at the rear of the combustion-chamber, 90

having a vertical opening and top conforming in shape to the lower portion of the boiler to form a narrow throat, a gate or shutter of similar shape at top, as the top of the pier to slide vertically in the opening, a lever whose short arm lifts and lowers the gate or shutter, and means to hold the long arm of the lever to its adjustment to regulate the width of or close the throat, as set forth.

In testimony of which invention I hereunto set my hand.

PERRY X JOHNSON.
